ABSTRACT: A mounting for a connector of the type which is projected through a shaped eyelet opening or the like and then turned out of phase therewith to achieve a connecting relationship, wherein two mounting elements or parts cooperate with the connector to hold it firmly in an extending position from a support so as to be advantageously presented for use while affording the necessary degree of rotative movement to the connector.

PATENTED DEC 22 1970

ATTORNEYS

QUARTER TURN CONNECTOR

The present invention relates generally to improvements for a connector of the type which, in practice, is projected through a shaped eyelet opening or the like and then turned out of phase therewith to achieve its connecting result, and more particularly, to an improved mounting for this type of connector which significantly facilitates the mounting thereof on a suitable support and in any desired location.

Fasteners or connectors of the above description are well known and in wide use, particularly for supporting canvas or tarpaulin. As generally understood, the canvas is provided along its periphery with numerous eyelets bounding shaped openings which, after accommodating the connector, results in the canvas being held in a supported position thereon by virtue of the connector then being turned out of phase with the shape of the eyelet opening so that removal of the canvas is prevented. This type of male and female connecting structure, namely a connector and eyelet opening in cooperating shapes, has the obvious commercial advantage of providing readily achieved connecting and disconnecting operation and is therefore widely used in refrigerated food carrying vehicles. In this specific end use, the practice is to form the refrigeration conduits with the canvases, and, in order to comply with the stringent health requirements of food carrying, it is also usually necessary to frequently clean the canvases. Thus, it is equally important to be able to readily remove the canvases for cleaning as it is to make sure that during use, the canvases are firmly supported in their desired operative arrangements.

Present techniques for mounting the connectors on food carrying vehicles as well as in other areas of use leave much to be desired in that the mounting usually consists of no more than means for firmly attaching the connector to the support wall and some bearing means to permit rotative movement of the connector. These connector mountings are not necessarily concerned with achieving the mounting with fewer and simpler parts and in a simple assembling operation, nor with facilitating the location of the connectors.

Broadly, it is an object of the present invention to provide a connector of the type as hereinbefore described and an improved mounting means therefor overcoming the foregoing and other shortcomings of the prior art. Specifically, it is an object to provide an improved connector mounting employing but two mounting parts cooperative with the connector in forming an easily assembled mounting which has the requisite strength to hold the connector firmly in its extended position from the support and which also allows the necessary rotative degree of movement to the connector.

A connector mounting demonstrating objects and advantages of the present invention includes a holding member having a radially expandable shank positionable in a mounting opening of the support, a connector of the type herein described which, in the assembly operation, is aligned with the holding member, and an interconnecting member, which may be a driving nail, which is driven home through the connector and holding member, and more particularly, engages with the holding member at its distal end such that the connector is held in a laterally extending position from the holding member while its proximal end is sized such that the connector is free to partake of rotative movement about the longitudinal axis of the interconnecting member, although with a selected degree of friction so that the connector retains its rotated position of movement.

The above brief description, as well as further objects, features and advantages of the present invention, would be more fully appreciated by reference to the following detailed description of a presently preferred, but nonetheless illustrative embodiment, in accordance with the present invention, when taken in conjunction with the accompanying drawings, wherein:

FIG. 1 is a side elevational view, partly in section, illustrating the various parts comprising the connector mounting of the present invention in a partially assembled condition;

FIG. 2 is similarly a side elevational view, in section taken on line 2-2 of FIG. 4, showing the connector mounting parts in their assembled condition;

FIG. 3 is a side elevational view, partly in section, illustrating the male connector or fastener in a 90° rotated position from its position depicted in FIG. 2;

FIG. 4 is a partial plan view projected from FIG. 2 and including an eyeleted canvas illustrated in phantom perspective; and

FIG. 5 is a plan view projected from FIG. 3 illustrating further structural details of the connector mounting.

Reference is now made to the drawings wherein there is shown a male connector and means for mounting the same, generally designated 10, demonstrating objects and advantages of the present invention. In the arrangement 10, the connector per se is identified by the reference numeral 12 and the other illustrated parts, soon to be described, are cooperating means which efficiently function to mount the connector 12 on a support S in a clearance position therefrom, as exemplified by the illustrated horizontally oriented position which readily permits supporting a canvas or tarpaulin C on the connector. To this end, the canvas C has appropriate female connecting structure such as that exemplified in FIG. 4 by the eyelet 14 bounding the opening 14a through which the connector 12 is adapted to be projected. As generally understood, after the projecting of the connector 12 through the eyelet opening 14a, the connector is given a quarter turn such that the shoulders 12a, formed by the enlarged size of the connector head 12b relative to its remaining cylindrical body 12c, extend on either side beyond the eyelet 14 and, as a consequence, prevent removal of the canvas C from its supported position on the connector body 12c. On the other hand, by merely rotating the connector head 12b another 90° so that it is aligned with the long dimension of the eyelet opening 14a, canvas C is of course readily removable from the connector. As just described, the so-called quarter turn connector 12 is well known both in construction and mode of operation, being particularly useful in refrigerated food carrying vehicles where the practice is to form the refrigeration conduits with canvases C and, in which in order to comply with the health requirements of food carrying, it is necessary to clean these canvases frequently which is of course facilitated by being able to readily remove the canvases from the vehicle preparatory to the cleaning thereof.

Constituting the present invention is the combination with the connector 12 of the parts now to be described which readily and efficiently permit the mounting of one or more connectors 12 on the support, where desired, and in the desired mounted condition both extending therefrom and freely rotatable. These parts, in order of assembly which provides the arrangement 10, includes a holding member 16, preferably fabricated of plastic, which initially is disposed in a loose fit within a predrilled through bore 18 in the support S. Holding member 16 includes a radially expandable split cylindrical shank 16a, and a larger diameter arcuate head 16b having a partial axial opening 16c which terminates at or just short of the longitudinal split 16d of the shank 16a. Completing the construction of the holding member 16 is a series of concentrically arranged projections 16e which provide the shank 16a with a gripping surface which effectively grips the wall 18 bounding the mounting opening in the support S. Holding member 16, as just described, is a conventional, commercially available article, but heretofore has been restricted in use as an anchor for brackets, panels or the like; nowhere in the prior practice has there been any appreciation or suggestion that the holding member 16 can be readily used as an efficient mounting for the connector 12 in accordance with the present invention.

Cooperating with the holding member 16 to form a mounting for the connector 12 is an interconnecting member 20 which may be an ordinary driving nail having a piercing point 20a, a medial body section 20b which may be either threaded, as illustrated, or provided with surface knurling which, as

generally understood, effectively serves as an engaging surface for completing the engagement of the member 20 with the holding member 16, and having finally an enlarged diameter head 20c. As may be best understood by a comparison of FIGS. 1 and 2, the arrangement 10 is achieved by aligning the axial opening 12b of the connector 12 with the partially completed axial opening 16c of the holding member 16 and then driving the interconnecting member 20 home through these aligned axial openings. The result is that the piercing point 20a of the member 20 is driven through the bottom wall bounding the opening 16c and into the split 16b and is effective, as clearly illustrated in FIGS. 2, 3, of forcing apart the two halves of the shank 16a such that the gripping projections 16e firmly engage the support wall 18. The engaging or gripping surfaces on the body 20b in turn engage with the surfaces of the holding member 16 which bound the now completed axial opening of the member 16, consisting of the combination of the previously noted opening 16c and the split 16b. As a result, the enlarged nail head 20c, which seats in a counterbore provided in the end of the axial opening 12b of the connector 20, is effective in holding the connector 20 in an extended position from the support S with the arcuate end portion of the connector 12 being in substantially conformal abutting engagement with the arcuate head 16b. Further, since the driving nail 20 is selected with a body diameter approximating that of the axial opening 12d, the member 12 is readily manipulated through rotative movement in order to achieve its engaging and disengaging positions relative to the canvas eyelet 14 or other similar cooperating connecting structure, but this occurs against a slight degree of friction which has been found effective to hold the member 12 in its rotated position of movement.

Although not shown, from the foregoing description it should be readily appreciated that the support S need not be limited to a wall or the like but could include a washer or other nonstationary member which is gripped by the expanding holding member 16 and, in this broad sense, provides support for the connector 12. Such an arrangement would be used to unite a connector 12 hereof to a canvas or other fabric-type material, this said material having an opening to accommodate the shank of the holding member 16 therethrough and having the portion thereof bounding this opening gripped between the washer and the large diameter head 16b of member 16.

A latitude of modification, change and substitution is intended in the foregoing disclosure and in some instances some features of the invention will be employed without a corresponding use of other features. Accordingly, it is appropriate that the appended claims be construed broadly and in a manner consistent with the spirit and scope of the invention herein.

I claim:

1. A mounting for a rotatable male connector comprising, in combination, a support having a mounting opening, a holding member including a radially expandable shank provided with a first sized axial opening having an operative position on said support with said shank projected through said mounting opening, a male connector provided with a second sized axial bore, and an interconnecting member of a prescribed diameter having an inserted operative position through the aligned axial openings of said holding member and said male connector, said interconnecting member prescribed diameter being of an extent relative to said first and second sized axial openings to respectively cause expansion of said holding member shank so as to firmly seat said holding member in said mounting opening and wherein said holding member includes an arcuate head portion and said male connector has an arcuate end portion disposed in substantially conformal abutting engagement with said arcuate head portion to allow turning movement of said male connector about said interconnecting member, whereby said male connector is rotatably disposed on said support.
2. A mounting for a rotatable male connector as defined in claim 1 wherein said holding member expandable shank has laterally extending concentrically arranged plural projections thereon adapted upon radially expansion of said shank to engage said support.
3. A mounting for a rotatable male connector as defined in claim 2 wherein said interconnecting member has an external engaging surface therealong effective to engage the surface of said mounting member bounding the axial opening thereof.
4. A mounting for a rotatable male connector as defined in claim 3 wherein said interconnecting member includes a front piercing section effective to complete said axial opening of said mounting member during the positioning of said interconnecting member in its said inserted position through said mounting member.
